US00D599503S

(12) **United States Design Patent**
Meritt

(10) **Patent No.:** **US D599,503 S**
(45) **Date of Patent:** **** Sep. 1, 2009**

(54) **FEEDING TUBE**

(75) Inventor: **Rick Meritt**, Gilmer, TX (US)

(73) Assignee: **Rick Meritt Investments, Ltd.**, Gilmer, TX (US)

(**) Term: **14 Years**

(21) Appl. No.: **29/296,700**

(22) Filed: **Oct. 25, 2007**

Related U.S. Application Data

(63) Continuation-in-part of application No. 11/160,611, filed on Jun. 30, 2005, which is a continuation-in-part of application No. 09/920,231, filed on Aug. 1, 2001, now Pat. No. 6,920,841.

(51) **LOC (9) Cl.** **30-03**

CLAIM

The ornamental design for a feeding tube, as shown and described.

DESCRIPTION

FIG. 1 is a perspective view of a feeding tube according to my new design;

FIG. 2 is a front elevation view of the feeding tube shown in FIG. 1;

FIG. 3 is a rear elevation view of the feeding tube shown in FIG. 1;

FIG. 4 is a left side elevation view of the feeding tube shown in FIG. 1;

FIG. 5 is a right side elevation view of the feeding tube shown in FIG. 1;

FIG. 6 is a top plan view of the feeding tube shown in FIG. 1; and,

FIG. 7 is a bottom plan view of the feeding tube shown in FIG. 1.

The broken lines are for illustrative purposes only and form no part of the claimed design.
